METHOD OF AND APPARATUS FOR HEAT TRANSFER

Earl F. Hubacker, Highland Park, Mich., assignor to Borg-Warner Corporation, a corporation of Illinois

Application December 11, 1937, Serial No. 179,249

9 Claims. (Cl. 62—116)

This invention relates to methods of and apparatus for heat transfer and particularly to improvements in refrigerating systems and methods and refrigerants for use therein.

This application is a continuation-in-part of my prior application, Serial No. 56,625, filed December 30, 1935, for method of and apparatus for heat transfer, and relates to subject matter of my prior application, Serial No. 80,337, dated May 18, 1936, for method of and apparatus for heat transfer.

A principal object of the invention is to provide an improvement in the art of refrigeration by means of which refrigeration at different temperatures may be produced simultaneously.

Another object of the invention is to provide a new and improved form of evaporator construction which is adapted to refrigerate simultaneously at different temperatures.

Another object of the invention is to provide a novel and improved refrigerating system including an evaporator which comprises a plurality of sections so arranged that a refrigerant body, comprising a plurality of liquid components, in each of the sections is exposed to substantially the same suction pressure, as a result of which refrigeration is produced in each of the sections at a temperature different than that of the other sections.

Another object of the invention is to provide in a refrigerating system, an evaporator having one section wherein refrigeration at a low temperature is produced and another section wherein refrigeration at a different temperature is produced.

Another object of the invention is to provide a novel form of heat transfer system wherein there is employed a liquid heat transfer or refrigerating medium which comprises a mixture or solution of two component fluids, said solution or mixture having a different boiling point than either of its components.

Another object of the invention is to provide a refrigerating system which is provided with a two-part evaporator, the liquid refrigerant mixture or solution in each of which part being exposed to substantially the same suction pressure, and the mixture or solution in one part of the evaporator boiling or evaporating at a lower temperature than that at which the mixture or solution boils in the other part of the evaporator.

Another object of the invention is to provide in a refrigerating system an evaporator which will operate to produce refrigeration at two different temperatures.

Another object of the invention is to provide a new and improved form of refrigerator construction having a plurality of refrigerated zones, each zone having different temperature and relative humidity conditions than those of the other zones.

Another object of the invention is to provide a novel process of refrigeration by means of which refrigeration at a plurality of different temperatures may be produced in a system simultaneously.

Another object of the invention is to provide new and improved forms of refrigerating apparatus which are useful generally in the refrigeration art and independently of the new and improved form of two-temperature refrigeration herein disclosed.

For better understanding of the invention, its advantages and objects, reference may be had to the following specification taken in conjunction with the accompanying drawings, of which there are seven sheets, and in which:

Fig. 1 is a view, somewhat diagrammatic, illustrating the application of my invention to a refrigerating system of the compressor, condenser, expander type;

Fig. 2 is a side elevational view partially broken away of the evaporator part of the system disclosed in Fig. 1;

Fig. 3 is a side elevational view (certain parts being broken away and others being shown in section) of a modified form of evaporator construction, and in connection with which a high side float is employed;

Fig. 4 is a diagrammatic plan view of the refrigerant lines of the evaporator illustrated in Fig. 3;

Fig. 5 is a front elevational view (certain parts being broken away and others being shown in section) of the evaporator illustrated in Fig. 3;

Fig. 6 is a horizontal sectional view taken generally in a plane along the line 6—6 of Fig. 5;

Fig. 7 is a vertical sectional view through the needle valve of the high side float, and taken generally along the line 7—7 of Fig. 3;

Fig. 8 is a side elevational view (certain of the parts being broken away, others being shown in section, and others being omitted for the sake of clarity) of a modified form of evaporator embodying a low side float type of refrigerant control;

Fig. 9 is a front elevational view of the evaporator illustrated in Fig. 8;

Fig. 10 is a horizontal sectional view taken along the line 10—10 of Fig. 9;

Fig. 11 is a vertical sectional view through the low side float assembly of the evaporator illustrated in Figs. 8, 9 and 10;

Fig. 12 is a horizontal sectional view of the low side float assembly, taken generally in a plane along the line 12—12 of Fig. 11;

Figs. 13 and 14 are sectional views illustrating details of some of the refrigerant headers employed in the construction illustrated in Fig. 9;

Figs. 15 and 16 are vapor pressure curves for various concentrations of dichlorodifluoromethane and sulphur dioxide, one of the refrigerant mixtures which may be employed in the systems herein disclosed;

Fig. 17 is an iso-therm on pressure composition diagram curve; and

Fig. 18 is an iso-bar on temperature composition diagram curve.

For the purpose of illustrating the invention, there is disclosed a refrigerating apparatus of the compressor, condenser, evaporator type, although it is to be understood that the invention herein disclosed and relating to the production of refrigeration at two or more different temperatures simultaneously by the employment of an evaporator construction having two or more sections and a refrigerant medium comprising a plurality of liquid components is applicable to other types of refrigerating systems.

In Fig. 1 of the drawings herein, there is disclosed a refrigerating apparatus of the compressor, condenser, expander type. The system as illustrated includes a source of power, such as an electric motor 10, a compressor 12 driven by the motor 10 through the intermediary of a belt and pulley drive, a condenser 14, a liquid receiver 15, an evaporator 16, a liquid refrigerant flow control device, such as a high side float 17, the compressor, condenser, receiver, high side float and evaporator being connected in a closed system through which refrigerant is circulated, and a temperature responsive device 18 controlling a switch 20 which controls the motor circuit 22. The temperature responsive device 18, as illustrated, may be thermally associated with the evaporator 16 and operate a switch 20 controlling the motor circuit, so that the compressor 12 may be operated to supply refrigerant to the evaporator when the temperature thereof raises above a desirable degree. The switch 20 may be set so as to maintain the temperature of that part of the evaporator 16 with which the thermostatic bulb 18 is associated within any desired degree of temperature range during the on and off cycles of operation of the condensing unit.

The evaporator 16 is illustrated as being arranged within a heat insulated compartment and may comprise a freezing section or part indicated generally at 24, disposed within a closed compartment formed by a sleeve 26, and an air cooling section or part 28 arranged externally of the sleeve 26 and exposed to the air within the heat insulated compartment for cooling the same, as well as whatever may be disposed in such compartment.

The sleeve 26 may comprise a metal shell secured to the upper metallic lining of the provision compartment and which is adapted to enclose the freezing section 24 of the evaporator so as to shield the same from the air circulating within the provision compartment, and so as to permit different temperature and humidity conditions to be created within the shell 26 than

exists outside thereof and within the provision compartment. It is, of course, contemplated that a door controlled opening shall be provided so as to permit introduction and removal of provisions into the shell 26, the interior of which hereafter will be referred to, for the sake of convenience, as the freezer section or zone of the evaporator. The shell or sleeve 26 may, of course, be made out of any material desired, if a greater or lesser degree of insulation is desired than is provided by the metallic sleeve 26.

The freezing section of the evaporator may comprise a header 31, a length of copper tubing formed to provide coils and arranged so as to provide a series of shelves 32 and upon which shelves, trays 33 may be disposed. Liquid refrigerant from the condenser 14 may be fed to the bottom shelf 32 of the freezer section by an insulated liquid line 35, and the flow of refrigerant from the receiver 15 to the freezer section of the evaporator through such liquid line 35 may be controlled in any suitable manner, such as by a high side float 17.

The upper end of the coil of the freezer section may be connected to and discharge into the header 31. The header 31 may also be connected directly to the bottom of the freezing coil 32 by a circulating pipe 37.

The air cooling section or zone of the evaporator indicated generally at 28 may comprise a pair of upper headers 34 and a pair of lower headers 36, the upper and lower headers being connected by a plurality of tubes 38 having fins 40. The upper headers 34 are connected to a liquid header 30 by pipes 42 which communicate with the header 30 below the normal liquid level therein, indicated at 35. A tube 44 may be provided to connect the bottom of the header 30 with a tube 46, which connects the lower headers 36, said tubes 44 and 46 preferably being arranged within the space enclosed by the shell 26. The headers 30 and 31 are in communication through a pair of tubes 43, one of which is disposed above the normal liquid level 35, and the other of which is disposed below the normal liquid level 35 in the headers 30 and 31. The vaporous refrigerant from both sections 24 and 28 of the evaporator passes into the upper portion of the header 30, from whence the suction line 48 conducts such refrigerant vapor to the intake side of the compressor 12. The tube 44 connecting the header 30 with a tube 46 serves to conduct liquid refrigerant downwardly to the lower headers 36 so that a circulation of liquid refrigerant is obtained within the air cooling section 28 of the evaporator, so as to carry bubbles of vaporous refrigerant upwardly through the tubes 38 and into the upper headers 34 and thence to the header 30 by way of conduits 42. In addition to the refrigerant employed in the system illustrated, it is contemplated that lubricant will be used in connection with the refrigerant medium and which will circulate therewith in the system for the purpose of lubricating the working parts thereof.

For obtaining different temperatures in the different sections of the evaporator, such as a lower temperature in the freezer section 24 than in the air cooling section 28, there may be employed as a refrigerant medium a liquid which comprises a mixture or solution of two or more refrigerant components, said liquid having a different boiling point than any of its components. Example of refrigerant mediums comprising a

mixture or solution of two or more refrigerant components are:

Sulphur dioxide (SO_2) and carbon tetrachloride (CCl_4)

Sulphur dioxide (SO_2) and (F-12) dichlorodifluoromethane (CCl_2F_2)

Sulphur dioxide (SO_2) and (F-11) trichloromonofluoromethane (CCl_3F)

Sulphur dioxide (SO_2) and (F-21) dichloromonofluoromethane (CHCl_2F)

Sulphur dioxide (SO_2) and ethyl chloride ($\text{C}_2\text{H}_5\text{Cl}$)

Sulphur dioxide (SO_2) and methyl chloride (CH_3Cl)

Sulphur dioxide (SO_2) and methylene chloride (CH_2Cl_2)

Sulphur dioxide (SO_2) and propane (C_3H_8)

Sulphur dioxide (SO_2) and normal butane (C_4H_{10})

Sulphur dioxide (SO_2) and isobutane (C_4H_{10})

Sulphur dioxide (SO_2) and dimethyl ether ($(\text{CH}_3)_2\text{O}$)

Sulphur dioxide (SO_2) and methyl formate ($\text{C}_2\text{H}_4\text{O}_2$)

Sulphur dioxide (SO_2) and dibutyl phthalate $\text{C}_8\text{H}_{14}(\text{COOC}_4\text{H}_9)_2$

Sulphur dioxide (SO_2) and dimethyl phthalate $\text{C}_8\text{H}_{14}(\text{COOCH}_3)_2$

Sulphur dioxide (SO_2) and methyl alcohol (CH_3OH)

Sulphur dioxide (SO_2) and monochlorobenzene ($\text{C}_6\text{H}_5\text{Cl}$)

Sulphur dioxide (SO_2) and methyl isobutyl ketone ($\text{CH}_3\text{COC}_4\text{H}_9$)

Sulphur dioxide (SO_2) and isopropyl acetate ($\text{CH}_3\text{COOC}_3\text{H}_7$)

Sulphur dioxide (SO_2) and amyl chloride ($\text{C}_5\text{H}_11\text{Cl}$)

Methyl chloride (CH_3Cl) and methylene chloride (CH_2Cl_2)

Methyl chloride (CH_3Cl) and isopropyl acetate ($\text{CH}_3\text{COOC}_3\text{H}_7$)

Methyl chloride (CH_3Cl) and methyl isobutyl ketone ($\text{CH}_3\text{COC}_4\text{H}_9$)

Methyl chloride (CH_3Cl) and dimethyl ether ($(\text{CH}_3)_2\text{O}$)

Methyl chloride (CH_3Cl) and methyl alcohol (CH_3OH)

Methyl chloride (CH_3Cl) and carbon tetrachloride (CCl_4)

Methyl chloride (CH_3Cl) and tetrachloroethane ($\text{C}_2\text{H}_2\text{Cl}_4$)

Methyl chloride (CH_3Cl) and toluene ($\text{C}_6\text{H}_5\text{CH}_3$)

Methyl chloride (CH_3Cl) and tetrachloroethylene (C_2Cl_4)

Methyl chloride (CH_3Cl) and amyl chlorides ($\text{C}_5\text{H}_11\text{Cl}$)

Methyl chloride (CH_3Cl) and monochlorobenzene ($\text{C}_6\text{H}_5\text{Cl}$)

Methyl chloride (CH_3Cl) and normal butane (C_4H_{10})

Methyl chloride (CH_3Cl) and (F-12) dichlorodifluoromethane (CCl_2F_2)

Methyl chloride (CH_3Cl) and (F-11) trichloromonofluoromethane (CCl_3F)

Methyl chloride (CH_3Cl) and (F-114) dichlorotetrafluoroethane ($\text{C}_2\text{Cl}_2\text{F}_4$)

Methyl chloride (CH_3Cl) and (F-21) dichloromonofluoromethane (CHCl_2F)

Dichlorodifluoromethane (CCl_2F_2) (F-12) and (F-11) trichloromonofluoromethane (CCl_3F)

Dichlorodifluoromethane (CCl_2F_2) (F-12) and (F-21) dichloromonofluoromethane (CHCl_2F)

Dichlorodifluoromethane (CCl_2F_2) (F-12) and (F-114) dichlorotetrafluoroethane ($\text{C}_2\text{Cl}_2\text{F}_4$)

F-11, F-12, F-21 and F-114 are simply the commercial names of some of the refrigerants indicated and are used principally for the purpose of convenience. In addition to the foregoing mixtures or solutions, other mixtures or solutions of two or more components may be used.

Of the refrigerants in the foregoing list propane (C_3H_8), normal butane (C_4H_{10}) and isobutane (C_4H_{10}) are classified as aliphatic hydro-

10 carbon compounds; Ethyl chloride ($\text{C}_2\text{H}_5\text{Cl}$), methyl chloride (CH_3Cl), methylene chloride (CH_2Cl_2), amyl chloride ($\text{C}_5\text{H}_11\text{Cl}$), carbon tetrachloride (CCl_4), tetrachloroethane ($\text{C}_2\text{H}_2\text{Cl}_4$) and tetrachloroethylene (C_2Cl_4) are classified as halogen derivatives of aliphatic hydrocarbon compounds; and

15 Dichlorodifluoromethane (CCl_2F_2), trichloromonofluoromethane (CCl_3F), dichlorotetrafluoroethane ($\text{C}_2\text{Cl}_2\text{F}_4$) and dichloromonofluoromethane (CHCl_2F) may be classified as halogen derivatives of aliphatic hydrocarbon or as fluorine derivatives of an aliphatic halogen compound.

In designing an evaporator and selecting a refrigerant medium such as F-12 and SO_2 for this system, use is made of the curves shown in Figs. 15 to 18.

Figs. 15 and 16 are ordinary vapor pressure curves for the various concentrations of F-12 in SO_2 as indicated;

30 Fig. 17 is derived from Figs. 15 and 16 as follows: The pressure in pounds per square inch absolute is plotted against the per cent F-12 at various temperature points. At 10% concentration of F-12 and a temperature of 20° F. the cor-

35 responding pressure of 28 lbs. is read from the vapor pressure curve and plotted at the point indicated on Fig. 17. At 5% F-12 and 20° F. another pressure point 24 lbs. is indicated on the Fig. 17. At 20% F-12, 20° F., a third pressure point 35 lbs. absolute is indicated on the graph (Fig. 15). These three points, and as many more as necessary, can be connected up to make a smooth curve, and this curve is known as isotherm on a pressure composition diagram. These

40 same curves can be plotted for as many temperatures as desired, as shown on this diagram (Fig. 17.)

Fig. 18 is an iso-bar or constant pressure on temperature composition diagram. This diagram is identical with Fig. 17, except that temperature is plotted against per cent F-12 instead of pressure. In this case, at 10% Freon composition and 20 lbs. per square inch absolute pressure, a cor-

50 responding temperature of 1° F. is read from the vapor pressure curve and the point indicated on the graph (Fig. 18). At 5% F-12 and 20 lbs. the temperature 9° F. is read from the vapor pressure curve, and also indicated on Fig. 18. As many more of these points as necessary may be plotted on the diagram and a smooth curve drawn which will be a 20 lbs. absolute pressure curve on the temperature composition diagram. As

55 many more of these curves may be drawn in the same manner for various pressures as are necessary.

60 In using these curves to design an evaporator to give a two-temperature effect, the first point determined is the temperature of the outside evaporator. If we select 25° F. as the temperature of the outside evaporator and refer to the iso-bar on temperature composition diagram, it will be observed that pure SO_2 vaporizes at 25° F. at 20 lbs. absolute. If we want, in the shelf portion of the evaporator, a temperature of 10° F., it will be necessary, at 20 lbs. absolute pres-

sure, to mix with the SO_2 approximately 5% F-12. This can be determined by following the 20 lb. line down to the 10° F. point on the iso-bar on the temperature composition diagram.

Theoretically, if we supply to the shelves of the evaporator, a mixture of 5% F-12 in SO_2 at 20 lbs. absolute pressure, we will get a shelf temperature of 10° F. F-12 will come off of this mixture in the gas phase in a much higher concentration than 5%, and will thereby reduce the concentration of F-12 eventually to 0%. The almost pure SO_2 will then feed over into the outside evaporator, and at 20 lbs. absolute will vaporize at approximately 25° F.

In actual performance, an evaporator, as illustrated in Fig. 1, with 5% concentration F-12 entering the shelves will not give a temperature of 10° at 20 lbs. absolute. This is due to the fact that, first, the liquid refrigerant mixture must be reduced in temperature to the boiling temperature, and this reduction in temperature is obtained by vaporizing a high concentration of F-12 so that the final concentration is something less than 5%. Second, in cooling the shelves, more heat is added to the mixture and the final temperature obtained is an average between the boiling point of the initial concentration and the concentration leaving the shelves. Apparently we are able to obtain approximately one-half of the theoretical spread.

This temperature spread, however, will vary materially with the load on the cabinet. This is due to the fact that the available refrigeration per pound of mixture circulated is constant, and since more pounds of refrigerant or mixture are circulated at higher loads, more refrigeration is available at the lower temperature level.

In a system of this type, the addition of F-12 tends to increase the condenser head pressure and thereby increase the power input to the compressor. However, it has been found that in a well built compressor with low friction losses, the increase in head pressure increases the power input very slightly, and there is a tendency for an over-all gain in power consumption per day because the suction pressure increases slightly, and the outside evaporator is more efficient due to the improved ebullition because of the increased quantity of gas flowing through it.

The mixture just described may be classified by what is commonly termed a minimum boiling point mixture. In addition to this there are other types of mixtures, known as a normal boiling point and a maximum boiling point. The normal boiling point mixture would be represented by a mixture such as F-12 and F-21. In this mixture the boiling point is always between the boiling point of the pure constituents. The general design of a system employing such a mixture would be similar to the SO_2 F-12 system in that a small concentration of F-12 would be added to F-21, and this mixture fed to the shelves where F-12 would vaporize much more rapidly than F-21 and reduce the mixture to substantially pure F-21, which would be fed to the outside evaporator.

Another example of the normal boiling point mixture would be one in which one component is relatively non-volatile. An example of this system would be SO_2 —dibutyl phthalate. In this system the dibutyl phthalate would stay in the outside evaporator and practically pure SO_2 would be fed to the shelves. The dibutyl phthalate mixing with the pure SO_2 would cause a

rise in boiling point so that the temperature in the shelves would be correspondingly lower than the outside evaporator temperature.

In a mixture system having a maximum boiling point such as dimethyl ether— SO_2 , if a concentration of 10% dimethyl ether was fed to the shelves the gas leaving would contain less than 10% dimethyl ether. This would mean that the concentration of dimethyl ether in the liquid 5 would increase and this increase would continue 10 until the liquid composition was approximately 30%, at which concentration the gas leaving would also be 30%. The boiling point would go up as the concentration increased and the composition of the liquid in the outer evaporator 15 would be 30%.

In operation a system such as the one illustrated in Figs. 1 and 2 is charged with a quantity 20 of refrigerant medium, which is a mixture or solution of a plurality of components, such as a 5% solution of F-12 in SO_2 . The terms solution or mixture, as used herein, are not to be construed only in their technical sense, but are intended to refer to a body of a plurality of components or ingredients associated in whatever manner such components or ingredients will associate when placed together in a system such as a refrigerating system.

Where the evaporator comprises a plurality of 30 sections, such as illustrated in Figs. 1 and 2, the refrigerant medium will operate to produce different temperature conditions in each section of the evaporator, because the refrigerant solution or mixture in one section of the evaporator will 35 contain a different percentage of the components of the refrigerant than the solution or mixture in the other section of the evaporator and there will be a temperature differential between the temperatures of the different sections of the 40 evaporator, because the solution in one section will boil at a different temperature than the solution in the other section. The temperature differential can be varied by using different percentages of the components of the refrigerating 45 medium, as may be observed from a study of the graphs illustrated in Figs. 15 to 18 inclusive.

The refrigerant medium in circulating through 50 the system is discharged from the compressor into the condenser where condensation of the vaporous refrigerant takes place and thence to the receiver from which it passes under the control of the high side float to the freezing coils 32 or the freezing section 24 of the evaporator, wherein a percentage of each of the components 55 of the refrigerant mixture or solution will boil off in going through the freezing coils, and the remainder of the mixture or solution will be discharged into the header 31.

The refrigerant in the freezing section 24 of 60 the evaporator, which comprise the freezing coils 32 and header 31, it will be observed is exposed substantially to the same suction pressure as the refrigerant within the air cooling section 28 of the evaporator. In passing through the freezing coils 32, the gas coming off of the refrigerant mixture will contain a greater percentage of the refrigerant component having the higher volatility or lower boiling point, with the result that the residual refrigerant which is discharged into the header 31 has a lower percentage of the higher volatile component in it than is present in the mixture or solution in the freezing coils 32. The mixture or refrigerant which is discharged into the header 31 passes into the header 70 30, and such refrigerant has a higher boiling

point than the boiling point of the solution in the freezing coils 32. Since the refrigerant in the coils 32 boils at a lower temperature than the refrigerant which is delivered to the coils of the air cooling section 28 of the evaporator, it will be apparent that a lower temperature will be produced in the freezing section of the evaporator than in the air cooling section of the evaporator.

The vaporous refrigerant from both sections of the evaporator passes into the upper portion of the header 30, from whence the suction line conducts such refrigerant vapor, together with whatever lubricant may be entrained therein, to the intake side of the compressor 12. The average composition of the gas passing through the suction line will always be the same as the average composition of the liquid entering the evaporator.

The refrigerant systems illustrated in Figs. 3 to 14 inclusive, operate to produce refrigeration at a plurality of different temperatures in substantially the same manner as the system illustrated in Figs. 1 and 2.

In Figs. 3 to 7 inclusive, there is illustrated a modified form of evaporator construction having a high side float valve for controlling the admission of liquid refrigerant from the condensing unit to the evaporator. In this embodiment of the invention, the evaporator comprises (Fig. 4) a freezer section indicated generally at 50 and an air cooling section indicated generally at 52. From the high side float indicated generally at 54, liquid refrigerant is fed by a conduit 56 through a heat interchanger indicated generally at 58, thence through a capillary tube 60 and from the capillary tube the liquid refrigerant is fed to the freezer section 50 of the evaporator. From the freezer section 50 of the evaporator refrigerant is fed by means of conduit 62 to the heat interchanger 58, thence through a conduit 64 to a tube 66 which connects the bottom two headers 68 of the air cooling section 52 of the evaporator. The refrigerant circulates upwardly through tubes which connect the lower headers 68 with upper headers 70 and the refrigerant vapors are taken from the upper headers 70 by cross tube 72 to which a suction line 74 is connected. The suction line 74 is coiled around the needle portion of the high side float 54 to provide a heat interchanger 76 between the suction gases and the liquid in the high side float. The suction line 74 then returns the refrigerant vapor to the intake side of a compressor. Apart from the evaporator and the high side float, the remainder of the system may be like that disclosed in Fig. 1.

The heat interchanger 58 aids in reducing the temperature of the refrigerant mixture after it leaves the high side float 54 and before it is fed to the freezer section 50. The capillary tube 60 arranged between the freezer section 50 and the heat interchanger 58 tends to prevent the vaporization of refrigerant before reaching the freezer section 50. In the freezer section 50, the addition of heat to the refrigerant will cause the evolution of vapor therein, and when the refrigerant employed is a minimum boiling point mixture or solution, as previously described, the component thereof having the lower boiling point will volatilize in the freezer section 50 as well as a small part of the component having the higher boiling point. The vaporization of practically all of the lower boiling point component in the freezer section 50 will result in the delivery

to the air cooling section 52 of the evaporator of the residual refrigerant having the higher boiling point and which will have very little of any of the lower boiling point component therein. In the air cooling section 52 of the evaporator, the higher boiling point component will volatilize to produce refrigeration at a higher temperature than the temperature at which the refrigerant in the freezer section 50 evaporates. As the two sections 50 and 52 of the evaporator are connected in series, substantially the same suction pressure will prevail throughout the evaporator, except for whatever friction losses might occur.

The high side float 54 comprises a receptacle, which, as illustrated in Figs. 3 and 5, is adapted to be arranged in an insulated space formed in the upper wall 80 of the cabinet which defines a heat insulated compartment within which the evaporator is arranged. Liquid refrigerant from the condensing unit is supplied through a conduit 55 past a strainer assembly 57 to the receptacle 59 of the high side float and wherein a float 61 is arranged. The bottom wall of the receptacle is provided with a sleeve 82 providing a refrigerant conduit 84 therein, and the conduit 56 is connected to the sleeve 82 and is in communication with the conduit 84 therein. The refrigerant conduit 84 is formed to provide a seat 86 for needle valve 88, the needle valve being operated by the float 61, and the float 61 being operable responsive to changes in liquid level within the receptacle 59. The conduit 56 forms the inside part of the heat exchanger 58, and the end of the conduit 56 after emerging from the heat exchanger 58 is connected to one end of the capillary tube 60, the other end of which is connected to one end of a U-shaped piece of tubing 90 arranged beneath and in good thermal contact with a shelf 92. The other end of the U-shaped piece of tubing is connected to a riser tube 94 which is connected to one end of a similar piece of tubing 90 arranged beneath and in good thermal contact with an upper shelf 92. The other end of the tubing 90, for the upper shelf, is connected by conduit 62 with one end of a large pipe 63 which forms the outer part of the heat exchanger 58. The tubing 90 and the connecting tube 94, comprises the freezer section 50 of the evaporator, and this section may be made out of a continuous piece of tubing bent to form the plurality of shelves. The shelves 92 are adapted for supporting trays, such as trays 33.

The air cooling section 52 of the evaporator, as illustrated in Figs. 3 to 7 inclusive, comprises a pair of vertically arranged sheet metal walls 96, a bottom wall 98, a back wall 100, a shield 102 and a door 104 which may be carried by the shield 102 and which is arranged to close the compartment defined by the side, back and bottom walls. A gasket 103 is associated with the shield 102 and the door 104 so as to provide a seal around the door. As the freezer section 50 and the cold storage zone 120 are otherwise closed, the closure 104 effectively separates the air within the freezer section and the cold storage section from the air within the provision compartment.

The freezer section 50 of the evaporator, as illustrated in Figs. 3 to 7 inclusive, is arranged within a sleeve 106, the back of which is closed by a plate 108 and the front of which sleeve is closed by the door 104. The sleeve 106 is adapted to be supported within an upper part of the

compartment defined by the side, back and bottom walls of the air cooling section of the evaporator in spaced relation to the side and back walls so that the zone refrigerated by the freezer section 50 will be enclosed independently of the walls which define the air cooling section of the evaporator. The shelves 92 of the freezer section of the evaporator are secured to and supported by the side walls of the sleeve 106. The remainder of the compartment formed in part by the side walls 96 may be provided with a plurality of shelves 110 adapted for supporting trays, such as 33 thereon.

The walls 96 which comprise part of a shell may each be formed of two sheets of metal welded together and formed so as to provide refrigerant ducts 112, lower headers 68 and upper headers 70. The lower headers 68, as illustrated, are horizontally arranged and communicate with the bottom ends of the ducts 112, while the upper headers 70 are horizontally arranged and communicate with the upper ends of the ducts 112. Fins 114 which serve to increase the effective surface of the walls 96 extend outwardly therefrom and into the path of the air which circulates within the heat insulated provision compartment.

The refrigerant, after having passed through the freezer section 50 of the evaporator and the heat exchanger 58, is conducted by conduit 64 down to the bottom of the evaporator where it connects with cross tube 66 which delivers refrigerant to the lower headers 68. The lower headers 68 distribute refrigerant to the ducts 112, and the refrigerant flows upwardly through the ducts 112 into the upper headers 70 and then by cross tube 72 to the suction line 74 through heat exchanger 76 and thence to the intake side of the compressor. The heat exchanger 76 is formed by coiling a part of the suction line 74 around the sleeve 82 of the high side float assembly.

The freezer section 50 of the evaporator, by employing one of the refrigerant mixtures heretofore discussed, will operate to produce refrigeration at a selected low temperature and refrigeration at a higher temperature will be produced in the air cooling section of the evaporator. The air cooling section of the evaporator will operate to cool the air circulating within the provision compartment down to some desired cabinet temperature. The space within the shell of the air cooling evaporator and below the freezer section 50 therein, however, will have a temperature materially lower than the temperature of the air in the provision compartment and yet higher than the temperature in the freezer section of the evaporator, and this part of the evaporator provides a cold storage zone, which is indicated generally by the reference character 120. This cold storage zone may be employed for freezing water or for the storage of provisions at a temperature at which refrigeration is produced in the air cooling section of the evaporator; say in the neighborhood of 25° to 30° F., whereas the freezing section 50 may, by the selection of the proper refrigerant mixture, be operated at a temperature much lower than that in the air cooling section; say in the neighborhood of 0° to 10° F.; thus, there is provided in the evaporator construction illustrated in Figs. 3 to 7 inclusive, two different zones of refrigeration in addition to the higher temperature zone formed by the provision compartment.

The space within which the high side float is

arranged is separated from the provision compartment by an insulated wall 122 and a sealing ring 124 so as to prevent excess heat loss through this space.

In the embodiment of the invention illustrated in Figs. 8 to 14 inclusive, the evaporator comprises in general a metallic sleeve 150, a refrigerant header 152, a plurality of U-shaped tubes 154 having their ends in communication with the interior of the header 152 and arranged outwardly of the sleeve 150 and in good thermal contact therewith, and a length of tubing, indicated generally at 156, bent to form a series of shelves 158 and which are arranged within the sleeve 150 and supported by the side walls thereof.

The evaporator illustrated in Figs. 8 to 14 inclusive, is adapted to be arranged within a heat insulated or other compartment like the other evaporators disclosed herein, and a condensing unit like that illustrated in Fig. 1 may be employed in connection with the evaporator illustrated in Figs. 8 to 14 inclusive. The thermostat bulb 18 which controls the switch in the motor circuit 22 may, in connection with the evaporators illustrated in Figs. 3 to 14 inclusive, be thermally associated with the air cooling or outside section of the evaporator. In the evaporator illustrated in Figs. 8 to 14 inclusive, the air cooling or outside section of the evaporator comprises the tubes 154 and the fins 155 secured thereto, said fins being adapted to project into the path of the air circulating within the compartment in which the evaporator is arranged. The freezer section of the evaporator comprises the refrigerated shelves 158, which are arranged within the interior of the sleeve 150 so that the compartment defined by the sleeve 150 forms a low temperature fast freezing zone. The evaporator illustrated in Figs. 8 to 14 inclusive may have a shield, a closure and a gasket for the front thereof, like the shield 102, the closure 104 and the gasket 103 illustrated in Figs. 3 to 7 inclusive, and the open front end of the sleeve 150 is adapted to be closed by such a door so as to separate the interior of the sleeve 150 from the air outside thereof and to prevent any material circulation of air therebetween.

The header 152 is horizontally arranged at the top of the sleeve 150 and the fins 155 are vertically arranged and secured to the tubes 154 and the header 152 such as by soldering so as to provide good thermal conduction therebetween. The rear end of the sleeve 150 is closed by a back wall 160. The shelves 158 each include a relatively flat sheet metal plate or tray 162 to the underside of which the tubing 156 is secured, such as by soldering so as to provide good thermal contact between the plate 162 and the tubing 156. The shelves 158 are adapted to support trays, like the trays 33, and are supported from the side walls of the sleeve 150 by pins 164. The side edges of the plates 162 are spaced from the sides of the sleeve 150 so as to reduce the flow of heat between the sleeve 150 and the plates 162.

Liquid refrigerant is fed to the bottom one of the shelves 158 by conduit 166, and the liquid refrigerant flows in series through the shelves which are connected by riser conduits 168. From the top one of the shelves the refrigerant flows upwardly through a riser conduit 170 to a header 172. From this header 172 there extends downwardly to the bottom shelf a recirculating tube 174 having a liquid trap portion 176. The bottom end of the tube 174 is connected to the intake

end of the tubing 158 which forms the bottom one of the shelves.

The refrigerant header (Figs. 11 and 12) contains a float operated valve mechanism and is adapted to contain and collect liquid refrigerant so as to be able to supply it to the tubes 154, the upper ends of which open into the bottom of the header.

The header comprises a cylindrical shell having a body 180 arranged to close the open end thereof and held in place by turning over the edges of the shell. The body 180 is provided with a valve body opening 182 and a suction passageway 184 therein. A tube 186 has one end pressed into the suction passageway 184 and the other end is turned downwardly and terminates inside of and slightly above the bottom of a cup 188. A plurality of wicks 190 may be hung over the edge of the cup so as to have a part depending inside of the cup to adjacent the bottom thereof and a portion depending outside of the cup to a point below the liquid level in the header 152. The wicks 190 serve to convey oil into the bottom of the cup where, when the oil rises above the bottom end of the tube 186, the gas pressure within the header 152 will force slugs of oil into the tube and the suction passageway 184.

A valve body 192 is arranged within the bore 182 and outwardly of the body 180 which forms the front wall of the header, the valve body 192 is provided with an enlarged flange portion 194. A head 196 has connected to it a suction line 198 and a liquid line 200. The valve body 192 is adapted to be secured in place by the head 196, and the head 196 is adapted to be secured in place by a pair of bolts 202 which pass through aligned openings in the head 196 and the flange 194 and have their ends threaded into engagement with threaded portions of the body 180. Suitable gaskets 204 are provided between adjacent surfaces of the body 180, the flange 194 and the head 196, and the head 196 is provided with a passage which affords communication between the suction line 198 and an opening 206 in the flange 194 which communicates with the end of the suction passageway 184 in the body 180. The head 196 also is provided with a passageway which affords communication between the liquid line 200 and a filter chamber 208 formed in one end of the valve body 192. The valve body 192 is provided with an axially extending passageway 210 in which a needle valve seat 212 and a needle valve 214 are arranged. The conduit 166 which supplies liquid refrigerant to the bottom of the freezer section of the evaporator is connected at one end thereof to a passageway 216 formed in the body 180, and this passageway communicates with a laterally extending passageway 218 formed in the valve body 192. A strainer 209 is arranged in the filter chamber 208. The needle valve 214 is adapted to cooperate with the seat 212 to close the passageway 210 against the flow of refrigerant. The end of the needle valve 214 is pivoted at 220 to a bifurcated portion of a lever 222 pivoted at 224 to lugs 226 formed on the valve body 192. One end of the lever 222 is provided with a slot 228 and a pin 230 carried by a lever 232 is arranged in the slot and is adapted to move vertically for operating the lever 222 so as to cause the needle valve 214 to seat and unseat with respect to the needle valve seat 212. The lever 232 is fixed to one end of a shaft 234 journaled in an opening in the wall of a chamber 236. The chamber 236 is formed in part integral with the body 180 and is closed by a plate 238 removably secured to the

open side of the chamber 236, such as by a plurality of screws 240. The interior of the chamber 236 in which the needle valve and its operating mechanism are arranged is thereby separated from the interior of the header 152 so that whatever refrigerant passes the valve seat 212 cannot escape into the header 152 but is required to pass into the conduit 166. A float 242 arranged in the header 152 is carried by a U-shaped bracket 244. The shaft 234 is fixed to one arm of the bracket 244 and the other arm of the bracket 244 is pivoted in line with the shaft 234 at 246. A spring 248 may be arranged around the shaft 234 and between the outside wall of the chamber 236 and one arm of the bracket 244, so as to maintain the lever 232 on the inside of the chamber 236 adjacent the opening in the wall of the chamber 236, through which the shaft 234 projects, in order to seal such opening against the passage of liquid therethrough. The float 242 operates responsive to the level of liquid in the header 152 to open and close the needle valve.

The refrigerant, after passing the needle valve, is conducted by the conduit 166 to the bottom shelf of the freezer section of the evaporator. After passing through the freezer section of the evaporator, the refrigerant enters the header 172 where it is conducted by a tube 252 which forms the outer part of a heat exchanger 250 to an elbow 254 which is in communication with the interior of the header 152. The inner part of the heat exchanger 250 is formed by the liquid supply line 200 which receives liquid refrigerant from the condensing unit. The heat interchanger 250 serves to cool the liquid refrigerant coming from the condensing unit. After the refrigerant is discharged from the tube 252 and elbow 254 into the header 152, the liquid refrigerant is supplied by the header 152 to each of the tubes 154 of the air cooling section of the evaporator.

Thus, it will be seen that the refrigerant after passing through the needle valve 212, passes through the conduit 166, the tubing 158 which forms the shelves which constitute the freezer section of the evaporator, the header 172, the tube 252, elbow 254, header 152 and into tubes 154. In both the tubes 154 and the tubes 156 the evolution of refrigerant vapor occurs due to the addition of heat to the liquid refrigerant, and the refrigerant vapor collects in the upper part of the header 152 from whence it passes through the cup 188 and the tube 186 to the suction line 198 which returns the refrigerant vapor and oil entrained therein to the intake side of the compressor.

When a refrigerant mixture is used, such as one of the minimum boiling point mixtures heretofore described, the lower boiling point component thereof will volatilize in the tubing 156 which forms the freezer section of the evaporator and the refrigerant which will be supplied to the tubes 154 of the air cooling section of the evaporator will comprise the higher boiling point or lower volatile component. Thus, vaporization of refrigerant will take place at one temperature in the shelves 158 and at a higher temperature in the tubes 154. If other mixtures besides a minimum boiling point mixture are used, the operation of this evaporator would be as described in connection with such other mixtures. The recirculating tube 174 functions to keep the shelves 158 supplied with liquid refrigerant at all times in the event that vaporization of the lower boiling point component should take place so rapidly as to expel practically all of the refrigerant.

erant from the shelves through the riser 170. The heat exchanger 250 functions to cool the refrigerant mixture coming from the condensing unit prior to the time that such refrigerant mixture is supplied to the freezer section of the evaporator. While the evaporator illustrated in Figs. 8 to 14 inclusive has been designed particularly for use in connection with one of the refrigerant mixtures disclosed herein, and this evaporator as well as that disclosed in Figs. 3 to 7 inclusive is useful in connection with an ordinary standard refrigerant inasmuch as these evaporators have many improved characteristics and new qualities not present in evaporators heretofore known. For instance, in connection with the evaporator disclosed in Figs. 8 to 14 inclusive, fast freezing shelves are provided in connection with a low side float evaporator and ebullition of the liquid in the shelves is accomplished by causing the liquid to circulate through the shelves before entering the header 152.

The thermostat bulb which operates the switch in the motor circuit may be secured to the evaporator illustrated in Figs. 8, 9 and 10 by means of a clamp 205.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. The method of producing refrigeration which comprises forming a liquid solution of (SO_2) and (C_4H_{10}) , evaporating liquid from said solution to produce refrigeration at one temperature, transferring liquid from said solution to form a body of refrigerant at another point having a boiling point different than that of said solution, evaporating refrigerant from said body of refrigerant to produce refrigeration at a temperature different than that produced by evaporating refrigerant from said solution, condensing the refrigerant vapor and returning the same in liquid form to said solution.

2. An arrangement for producing refrigeration at a plurality of different temperatures in separate zones closed against the circulation of air therebetween including means defining a chamber forming a first refrigerating zone and having a closure for preventing the entry therein of the surrounding air when closed, means defining another chamber forming a second refrigerating zone likewise having a closure for shutting out the circulation thereto of the surrounding air when closed, a first evaporator in contact with the air in said first chamber adapted to produce freezing and a second evaporator in contact with the air in said second chamber adapted to produce cooling at a higher temperature, means including a single compressor and condenser unit connected in series with said two evaporators for subjecting the same to a common suction pressure, withdrawing vaporous refrigerant from the discharge end of said cooling evaporator, conditioning and delivering the same to the inlet end of said freezing evaporator, said arrangement being further particularly characterized by the combination therewith of a refrigerant medium made up by placing together a first refrigerant and a second refrigerant, said first refrigerant having a lower boiling range than the boiling range of said second refrigerant, said refrigerants

retaining said individual boiling range characteristics after being placed together whereby the passage of said medium in succession through said first and second evaporators results in the formation of a multiplicity of bodies of refrigerant due to the absorbing of heat from the air surrounding said evaporators, each of said successive bodies of refrigerant containing different percentages of said different refrigerants, and each successive body having a different higher boiling range.

3. In an arrangement of apparatus for producing refrigeration at different temperatures in separate chambers closed against the circulation of air therebetween including a first chamber having a closure member for preventing the entry therein of the surrounding air when in the closed position, a second chamber likewise having a closure member for shutting out the circulation thereto of the surrounding air when in the closed position, a first evaporator positioned in contact with the air within said first chamber for producing freezing, a second evaporator positioned in contact with the air within said second chamber for producing cooling at a higher temperature, means connecting said evaporators in series, means including a single compressor and condenser unit connected in series with said two evaporators for subjecting the same to a common suction pressure withdrawing vaporous refrigerant from the discharge end of said cooling evaporator, conditioning and delivering the same to the inlet end of said freezing evaporator, said arrangement being particularly characterized by the combination therewith of a refrigerant medium made up by placing together a first refrigerant and a second refrigerant, said first refrigerant having a lower volatile range than that of said second refrigerant, the resulting refrigerant medium retaining the property of fractionally distilling so that, on evaporation, different concentrations of said respective refrigerants will be obtained increasing in volatility as said refrigerant medium is drawn through said freezing evaporator and then through said cooling evaporator, and a thermostatic control thermally associated with said cooling evaporator and operable for controlling the operation of said compressor unit.

4. In an apparatus for producing refrigeration at a plurality of different temperatures in separate zones closed against the circulation of air therebetween including means defining the first refrigerating chamber, said chamber having a closure member for preventing the entry therein of the surrounding air when in closed position, means defining a second refrigerating chamber likewise having a closure member for shutting out the circulation thereto of the surrounding air when in closed position, a first evaporator in contact with the air in said first chamber adapted to produce freezing and a second evaporator in series with said first evaporator and positioned in contact with the air in said second chamber for producing cooling at a higher temperature, means including a single compressor and condenser unit connected in series with said two evaporators for subjecting said evaporators to the same suction pressure, adapted to withdraw vaporous refrigerant from the outlet end of said cooling evaporator, conditioning and returning the same to the inlet end of said freezing evaporator, said arrangement being further particularly characterized by the combination therewith of a refrigerant medium

made up by placing together a first refrigerant and a second refrigerant, said first refrigerant being sulphur dioxide (SO_2), said second refrigerant being C_4H_{10} , said refrigerants retaining said individual boiling range characteristics after being placed together resulting in said C_4H_{10} , fractionating off predominantly in said first evaporator to produce a freezing temperature in said first chamber and said SO_2 fractionating off predominantly in said second evaporator to produce cooling at a relatively higher temperature in said second chamber.

5. In an arrangement of apparatus for producing refrigeration at different temperatures in separate chambers closed against circulation of air therebetween including a first chamber having a closure member for preventing the entry therein of the surrounding air when in the closed position, a second chamber likewise having a closure member for shutting out the circulation thereto of the surrounding air when in the closed position, a first evaporator positioned in contact with the air within said first chamber for producing freezing, a second evaporator positioned in contact with the air within said second chamber for producing cooling at a higher temperature, means connecting said evaporators in series, means including a single compressor and condenser unit connected in series with said two evaporators for subjecting the same to a common suction pressure withdrawing vaporous refrigerant from the discharge end of said cooling evaporator conditioning and delivering the same to the inlet end of said freezing evaporator, said arrangement being particularly characterized by the combination therewith of a refrigerant medium made up by placing together a first refrigerant and a second refrigerant, said first refrigerant having a lower volatile range than that of said second refrigerant, said first refrigerant comprising an aliphatic hydrocarbon compound and said second refrigerant comprising sulphur dioxide (SO_2), said resulting mixture of refrigerant medium retaining the property of fractionally distilling so that said aliphatic hydrocarbon compound distills off predominantly in said freezing evaporator to produce freezing in said first chamber while said sulphur dioxide fractionates off predominantly in said cooling evaporator to produce cooling in said second chamber at a higher temperature.

6. In an arrangement of apparatus for producing refrigeration at different temperatures in separate chambers closed against the circulation of air therebetween including a first chamber having a closure member for preventing the entry therein of the surrounding air when in the closed position, a second chamber likewise having a closure member for shutting out the circulation thereto of the surrounding air when in the closed position, a first evaporator positioned in contact with the air within said first chamber for producing freezing, a second evaporator positioned in contact with the air within said second chamber for producing cooling at a higher temperature, means connecting said evaporators in series, means including a single compressor and condenser unit connected in series with said two evaporators for subjecting the same to a common suction pressure withdrawing vaporous refrigerant from the discharge end of said cooling evaporator conditioning and delivering the same to the inlet end of said freezing evaporator, said arrangement being particularly characterized by the combination therewith of a refrigerant medium

made up by placing together a first refrigerant and a second refrigerant, said first refrigerant having a lower volatile range than that of said second refrigerant, said first refrigerant comprising a halogen derivative of an aliphatic hydrocarbon compound and said second refrigerant comprising sulphur dioxide (SO_2), the resulting refrigerant medium retaining the property of fractionally distilling so that said halogen derivative of an aliphatic hydrocarbon compound evaporates predominantly in said freezing evaporator to produce freezing in said first chamber, while said sulphur dioxide evaporates predominantly in said second evaporator at a higher temperature to produce cooling in said second chamber.

7. In an arrangement of apparatus for producing refrigeration at different temperatures in separate chambers closed against the circulation of air therebetween including a first chamber having a closure member for preventing the entry therein of the surrounding air when in the closed position, a second chamber likewise having a closure member for shutting out the circulation thereto of the surrounding air when in the closed position, a first evaporator positioned in contact with the air within said first chamber for producing freezing, a second evaporator positioned in contact with the air within said second chamber for producing cooling at a higher temperature, means connecting said evaporators in series, means including a single compressor and condenser unit connected in series with said two evaporators for subjecting the same to a common suction pressure withdrawing vaporous refrigerant from the discharge end of said cooling evaporator conditioning and delivering the same to the inlet end of said freezing evaporator, said arrangement being particularly characterized by the combination therewith of a refrigerant medium made up by placing together a first refrigerant and a second refrigerant, said first refrigerant having a lower volatile range than that of said second refrigerant, said first refrigerant comprising C_3H_8 and said second refrigerant comprising SO_2 , the resulting refrigerant medium retaining the property of fractionally distilling so that said C_3H_8 evaporates predominantly in said freezing evaporators for producing freezing in said first chamber while said SO_2 evaporates predominantly in said second evaporator at a higher temperature for producing cooling in said second chamber.

8. In an arrangement of apparatus for producing refrigeration at different temperatures in separate chambers closed against the circulation of air therebetween including a first chamber having a closure member for preventing the entry therein of the surrounding air when in the closed position, a second chamber likewise having a closure member for shutting out the circulation thereto of the surrounding air when in the closed position, a first evaporator positioned in contact with the air within said first chamber for producing freezing, a second evaporator positioned in contact with the air within said second chamber for producing cooling at a higher temperature, means connecting said evaporators in series, means including a single compressor and condenser unit connected in series with said two evaporators for subjecting the same to a common suction pressure withdrawing vaporous refrigerant from the discharge end of said cooling evaporator conditioning and delivering the same to the inlet end of said freezing evaporator, said arrangement being particularly characterized by the combination therewith of a refrigerant me-

dium made up by placing together a first refrigerant and a second refrigerant, said first refrigerant having a lower volatile range than that of said second refrigerant, said first refrigerant comprising C_4H_{10} and said second refrigerant comprising SO_2 , the resulting refrigerant medium retaining the property of fractionally distilling so that said C_4H_{10} evaporates predominantly in said freezing evaporator to produce freezing in said first chamber while said SO_2 evaporates predominantly in said second evaporator at a higher temperature to produce cooling in said second chamber.

9. The method of producing refrigeration which comprises forming a refrigerant medium by placing together a plurality of liquid refrigerants of different volatility, one of which comprises

5 (SO_2), and another of which comprises a halogen derivative of an aliphatic hydrocarbon compound, evaporating the more volatile one of said refrigerants from said medium in a first evaporating zone to produce refrigeration at one temperature, transferring the resultant refrigerant medium to form a body of refrigerant in a second zone having a boiling point different than that of said medium in said first zone, evaporating refrigerant from said body to produce refrigeration at a temperature different from that produced by evaporating refrigerant from said medium in said first zone, condensing the refrigerant vapor and returning the same to again form said first named refrigerant medium.

10 15 EARL F. HUBACKER.

CERTIFICATE OF CORRECTION.

Patent No. 2,255,584.

September 9, 1941.

EARL F. HUBACKER.

It is hereby certified that error appears in the printed specification of the above numbered patent requiring correction as follows: Page 3, second column, line 41, for "(Fig. 15)" read --(Fig. 17)--; and that the said Letters Patent should be read with this correction therein that the same may conform to the record of the case in the Patent Office.

Signed and sealed this 4th day of November, A. D. 1941.

Henry Van Arsdale,

(Seal)

Acting Commissioner of Patents.
